ELECTROMAGNETIC PICKUP

Harvey F. Schwarz, London, England

Application October 13, 1945, Serial No. 623,277
In Great Britain June 18, 1945

14 Claims. (Cl. 179—100.41)

1

My invention relates to an electromagnetic sound reproducer or phonograph pick-up which finds particular utility in providing faithful high fidelity reproduction from laterally cut recordings embracing a high frequency range.

In the reproduction of laterally cut recordings it is necessary that the reproducing stylus be mounted for free lateral movement so as to be moved from side to side in strict conformity with the vibrations recorded on the sound track. It must have extreme rigidity in the axial direction or lengthwise of the sound track to minimise distortion. In pick-ups of the electromagnetic type it is also required that the magnetic flux vary linearly with the displacement of the stylus from an intermediate or neutral position. Furthermore, to prevent resonance effects and similar forms of distortion, it is required that the natural period of lateral vibration of the stylus be well below the lowest frequency desired to be reproduced and it is also necessary that the pick-up assembly and stylus each have a minimum weight and inertia to minimise the loading on the walls of the record grooves, particularly at high frequencies or sounds having steep wave fronts, and in the event the record is not quite flat. As a matter of convenience it is also preferable to arrange for the ready replacement of the stylus.

The reproducers of the character referred to known prior to my invention do not meet these desirable conditions. In most constructions the stylus support depends upon the use of trunnions or upon the relative stiffness in two directions of a thin, flat member to provide rigidity in the longitudinal direction together with lateral flexibility. Such a construction provides at best a compromise in which insufficient longitudinal rigidity is obtained and in which the stylus has greater rigidity in the lateral direction than is desirable. This leads to distortion resulting from the longitudinal displacement of the stylus, and from the resonance of the stylus when reproducing low frequencies. A linear relation between the rate of change of flux and the displacement of the stylus is seldom obtained because of the prior attempts to use highly efficient magnetic circuits. Also in the prior constructions provision was made for replacing the stylus by a thumb screw type of clamp which added greatly to the weight of the stylus assembly and resulted in excessive loading on the sound track walls and rapid wearing of the records.

It is accordingly an object of my invention to provide a reproducer or pick-up of the electro-

2

magnetic type which overcomes the above noted disadvantages by reason of a novel magnetic circuit and an improved stylus mounting.

It is another object of my invention to provide a pick-up of the character set forth in the preceding paragraphs in which a material reduction in weight is obtained by the use of a greatly simplified magnetic circuit.

It is also an object of my invention to provide a pick-up of the character referred to in the preceding paragraphs in which the stylus holder is made extremely light in weight and constructed to have high intrinsic rigidity.

It is an additional object of my invention to provide a pick-up of the character referred to in the preceding paragraphs in which the stylus assembly is formed with a T-shape, lateral vibration of the stylus being accomplished by pivotal movement of the assembly about the longitudinal axis of the bar of the T, such movement being permitted by trunnion blocks of rubber or similar resilient material adhesively bonded to the extremes of the bar of the T-shape, whereby the relatively great length of the bar of the T effectively prevents movement of the stylus in a longitudinal direction.

It is also an object of my invention to provide a pick-up of the character heretofore described which includes a pair of simple opposed permanent bar magnets for establishing the required magnetic field.

It is a still further object of my invention to provide a pick-up of the character referred to hereinbefore in which the permanent magnet pole pieces are disposed between the rock bar and the record engaging end of said stylus, and as close to said stylus as possible.

It is an additional object of my invention to provide a pick-up of the character set forth in the preceding paragraphs which is formed as a pair of separable hinged halves normally held in closed position by a detent mechanism and which includes means operative in the closed position to hold the stylus in the proper relation to the other parts of the pick-up through clamping pressure exerted on the rubber trunnion blocks by the two halves of the assembly.

Other objects and advantages of my invention will be apparent from a study of the following specification read in connection with the accompanying drawings, wherein:

Fig. 1 is a perspective drawing illustrating the general form and appearance of a pick-up constructed in accordance with the preferred embodiment of my invention;

Fig. 2 is a longitudinal sectional view through the pick-up shown in Fig. 1 and illustrating the details of construction of a coil support and stylus mounting;

Fig. 3 is an underside view of the device shown in Fig. 2 and further illustrating the relative positions of the parts;

Fig. 4 is a fragmentary cross sectional view taken along the line IV-IV of Fig. 2; and

Fig. 5 is a perspective view of the stylus assembly showing the details of construction.

Referring to the drawings, I have illustrated therein the preferred embodiment of my invention as comprising a pick-up assembly formed as two separable halves 1 and 2 joined to each other by a hinged construction comprising a tongue 3 on the lower member 2 disposed within a longitudinally extending slot 4 formed in the upper member 1, a hinge pin 5 being passed longitudinally through the tongue 3 and the bosses 6 and 7 disposed on either side of the tongue 3 and defined by the slot 4. The upper part 1 of the assembly constitutes a cover for the lower part and serves also as a clamping mechanism for holding the stylus in an operative position as will subsequently appear.

When in use, the hinged halves are moved into juxtaposition as illustrated in Fig. 2 and are held in such position by a detent mechanism which may comprise a projection 8 formed on the upper half 1 and which enters a similarly contoured depression formed in the lower half 2. The rear portion 9 of the upper half 1 is given a cylindrical form and is bored as indicated at 10 and 11 to provide for attachment of a "tone arm" or swivel mounting providing for the traversal of the pick-up over the surface of the record during reproduction.

The bore 10 communicates with an interior space 12 permitting the electrical conductors comprising the output circuit of the pick-up to be connected respectively to a pair of connector elements 13 extending in a generally vertical direction through the lower half 2 and extending into a recess 14 formed in the under surface of the lower half. This recess and an upwardly extending bore 15 serve to house a pick-up coil 16 and may be normally closed by a dust cover 17 removably secured to the underside of the lower half 2 as by means of flat head countersunk screws 18.

The bore 15 preferably extends somewhat beyond the mid line of the lower half 2 at which point its diameter is reduced as indicated at 19 to provide a shoulder 20 against which the pick-up coil 16 may be seated. The pick-up coil 16 may be secured within the recess 15 as by means of shellac, varnish or other suitable adhesive.

As appears in Figs. 2 and 4, the reduced diameter bore 19 communicates with a longitudinally extending recess 21 which is preferably given a rectangular cross section and which serves to house a stylus assembly indicated generally by the reference character 22. The stylus assembly is preferably constructed along the lines illustrated in Figs. 2, 4 and 5 and comprises a formed T shaped member consisting of a rock bar portion 23 from the center of which depends a tapered cylindrical tube 24. The tube 24 is preferably contoured as shown in Fig. 4, to provide a short, straight cylindrical section 25 merging into a conical section 26 which is secured to or formed integrally with the transverse bar portion 23. The depending tubular portion 24 is preferably bored as indicated at 27 to receive a

sound track engaging stylus 28 formed preferably of sapphire or a similar jewel.

The bar portion 23 is by preference given a channel shaped cross section defined by a horizontally extending web 29 from opposite sides of which rise narrow flanges 30 and 31. The flanges 30 and 31 at the extreme ends of the bar portion 23 are given a somewhat greater width and are turned inwardly toward each other as shown at 32 and 33 to provide a quasicylindrical section to which trunnion blocks 34 and 35 formed of rubber or other like resilient material are secured, preferably as by means of a vulcanising or adhesive bonding process.

I have found that the complete stylus holder can conveniently be formed by a drawing operation—as for example by a machine similar to an eyelet forming machine.

The stylus assembly is mounted within the lower half 2 in the manner shown in Figs. 2 and 4 with the trunnion blocks 34 and 35 seated within the channel 21. The upper half 1 includes downwardly extending bosses 36 and 37 disposed to engage the upper surfaces of the blocks 34 and 35 respectively when the halves are in their closed positions to thereby exert a clamping pressure on the blocks to hold the stylus assembly firmly within the recess 21. With the parts so positioned the tubular portion of the stylus passes through the center of the coil 16 and extends below the lower cover 17 a sufficient distance to permit the stylus to engage the record surface and allow adequate clearance between the cover and the surface of the record.

By properly locating the channel 21 and by carefully controlling the location and alignment of the blocks 34 and 35 as through use of a jig or fixture during bonding or vulcanizing, proper alignment upon assembly is assured.

The ends of the coil 16 are preferably carried through the recess 14 and secured as by soldering to the exposed ends of the connector member 13, thus completing the electrical circuit between the coil and the output conductors.

The magnetic field for the device is furnished by a pair of simple rectangular permanent bar magnets 38 and 39 secured in any suitable manner within rectangular recesses 40 and 41 formed in the under surface of the lower half 2 and aligned with the coil supporting bore 15. The depth of the recess 14 is chosen to place the upper surface of the magnets 38 and 39 substantially in contact with the lower surface of the coil 16. While the magnets 38 and 39 can be secured within the recesses 40 and 41 by any suitable means, as by means of screws or clamps, I have found that an adequately secure mounting is provided by making the recess and magnet dimensions conform closely and by using a suitable adhesive for holding the magnets in place.

The magnets are placed with unlike poles on opposite sides of the stylus assembly 22 and are spaced apart a distance substantially equal to the internal diameter of the coil 16, a distance which is somewhat greater than the maximum amplitude of vibration required of the stylus 22. Furthermore the magnets are given a width in the longitudinal direction (at right angles to the direction of stylus motion) which is large compared to the diameter of the stylus. By this means there is produced across the gap between the opposed faces of the bar magnets a substantially uniform magnetic field of considerable strength. The external magnetic circuit comprises the leakage path through the air and

through the body of the pick-up from the extreme ends of the magnet. The tubular portion 24 of the stylus assembly constitutes a shunt magnetic circuit joining the midpoints of the air gap and external portions of the magnetic circuit. Therefore, when the stylus portion 24 is positioned centrally between adjacent faces of the magnets 38 and 39, substantially no flux will flow through the stylus. However, a lateral displacement of the stylus to bring the stylus nearer one of the magnets and further from the other will unbalance the magnetic field and cause a flux to flow in one direction through the stylus. A displacement in the opposite direction will result in a flux flow through the stylus in the reverse direction. Because the magnetic field extending from pole to pole of the magnets 38 and 39 is uniform and because the extent of the lateral movement of the stylus is normally smaller than the spacing between the adjacent magnet faces the flux change through the stylus bears a substantially linear relationship to the magnitude of the displacement.

I have found that with a pick-up constructed as described, the stylus has great flexibility in the lateral direction and a natural period of vibration in that direction which is substantially lower than the lowest record frequency desired to be reproduced. Furthermore, the stylus presents extreme rigidity in the longitudinal direction and is not subjected to any material displacement in the longitudinal direction during operation. Faithful reproduction may be obtained up to frequencies as high as 12,000 cycles per second.

Attention is furthermore directed to the ease with which the stylus may be replaced as may be required by the wear resulting from continued use of the device. Replacing a stylus is accomplished simply and easily by hingedly moving the halves 1 and 2 away from each other whereby the complete stylus assembly 22 may be lifted upwardly from the channel 21 and replaced by a new stylus of like construction.

Also, the total weight of the pick-up is considerably reduced by the simplified magnet structure disclosed herein.

While I have shown and described the preferred embodiment of my invention I do not desire to be limited to the details of construction which have been shown and described herein except as defined in the appended claims.

I claim:

1. In an electromagnetic phonograph pick-up, the combination of: a body member formed of a light weight non-magnetic material; a pick-up coil mounted in a recess formed in one surface of said body; an armature of magnetic material extended axially through said coil; and a pair of simple permanent bar magnets disposed on opposite sides of said armature and extending along a line normal to the length of said armature, said magnets being secured within an elongated channel formed in said one surface of said body member, said magnets extending over the surface of said coil to hold said coil within said recess.

2. In a stylus assembly for an electromagnetic phonograph pick-up, the combination of: a tubular stylus shank formed of magnetic material; a pointed record engaging stylus secured in one end of said shank; a rock-bar secured to the other end of said shank at right angles thereto and extending substantially equal distances from said shank; and a pair of trunnion blocks secured to the ends of said rock bar, said trunnion

blocks being formed of a resilient material having a low modulus of rigidity and great elasticity permitting angular movement of said rock bar in response to lateral displacement of said stylus.

3. In a stylus assembly for an electromagnetic phonograph pick-up, the combination of: a tubular stylus shank formed of magnetic material; a pointed record engaging stylus secured in one end of said shank; a rock-bar secured to the other end of said shank at right angles thereto and extending substantially equal distances from said shank; and a pair of trunnion blocks adhesively bonded to the ends of said rock bar, said trunnion blocks being formed of a resilient material having a low modulus of rigidity and great elasticity, permitting angular movement of said rock bar in response to lateral displacement of said stylus.

4. In a stylus assembly for an electromagnetic phonograph pick-up, the combination of: a tubular stylus shank formed of magnetic material; a pointed record engaging stylus secured in one end of said shank; a rock bar secured to the other end of said shank at right angles thereto and extending substantially equal distances from said shank, said rock bar having a channel shaped cross section disposed with the plane of the web thereof at right angles to said shank; and a pair of trunnion blocks secured to the ends of said rock bar, said trunnion blocks being formed of a resilient material having a low modulus of rigidity and great elasticity permitting angular movement of said rock bar in response to lateral displacement of said stylus.

5. In a stylus assembly for an electromagnetic phonograph pick-up, the combination of: a rock bar of channel shaped cross section; trunnion blocks formed of a resilient material having physical properties similar to those of vulcanized rubber adhesively bonded to opposite ends of said rock bar; and a tubular stylus shank secured to said rock bar intermediate the ends thereof and at right angles to the length thereof, said shank having a generally tapered form disposed with the larger end at said rock bar, said shank having a substantially constant wall thickness along its length.

6. In a stylus assembly for an electromagnetic phonograph pick-up, the combination of: a rock bar of channel shaped cross section; trunnion blocks formed of a resilient material having physical properties similar to those of vulcanized rubber adhesively bonded to opposite ends of said rock bar; and a tubular stylus shank secured to said rock bar intermediate the ends thereof and at right angles to the length thereof; said shank having a cylindrical section spaced from said rock bar by a frusto-conical section disposed with the larger base at said rock bar, said shank having a substantially constant wall thickness along its length.

7. In a stylus assembly for an electromagnetic phonograph pick-up, the combination of: a tubular stylus shank formed of magnetic material; a pointed record engaging stylus secured in one end of said shank; a rock bar secured to the other end of said shank at right angles thereto and extending substantially equal distances from said shank, said rock bar having a channel shaped cross section disposed with the plane of the web thereof at right angles to said shank, the ends of said rock bar having a quasi-tubular form defined by upwardly and inwardly curving leg extensions of said channel shape; and a pair of trunnion blocks secured to the ends of said rock

bar, said trunnion blocks being formed of a resilient material having a low modulus of rigidity and great elasticity.

8. In an electromagnetic phonograph pick-up, the combination of: a body member formed of a light weight non-magnetic material; a pick-up coil mounted in a pocket extending inwardly from one surface of said body; a stylus assembly comprising a rock bar, a shank portion extended at right angles to said rock bar and disposed intermediate the ends thereof, and elastic trunnion blocks bonded to the ends of said rock bar; recess means in the other surface of said body for receiving said blocks and holding said stylus assembly in a position extending said shank axially through said coil; and means clamping said trunnion blocks in said recess.

9. In an electromagnetic phonograph pick-up, the combination of: a body member formed of a light weight non-magnetic material; a pick-up coil mounted in a pocket extending inwardly from one surface of said body; a stylus assembly comprising a rock bar, a shank portion extended at right angles to said rock bar and disposed midway of the ends thereof, and elastic trunnion blocks bonded to the ends of said rock bar; and means for clamping said blocks against the other surface of said body in positions extending said shank axially through said coil and disposing the length of said rock bar at right angles to the direction of desired movement of said stylus shank, whereby said desired movement is permitted by the angular movement of said rock bar torsionally distorting said elastic blocks.

10. In an electromagnetic phonograph pick-up, the combination of: a body member formed of a light weight non-magnetic material; a cover member hingedly attached to said body member for swinging movement between open and closed positions; a pick-up coil mounted in a pocket extending inwardly from one surface of said body; a stylus assembly comprising a rock bar, a shank portion extended at right angles to said rock bar and disposed midway of the ends thereof, and elastic trunnion blocks bonded to the ends of said rock bar; recess means in the other surface of said body for receiving said blocks and holding said stylus assembly in a position extending said shank axially through said coil; means on said cover member disposed to engage said blocks in said closed position of said cover and clamp said trunnion blocks in said recess; and means for releasably holding said cover in said closed position, whereby moving said cover to said open position permits removal and replacement of said stylus assembly.

11. In an electromagnetic phonograph pick-up, the combination of: a body member, a stylus assembly comprising a tubular stylus shank formed of magnetic material, a pointed record-engaging stylus secured in one end of said shank, and a rock bar secured to the other end of said shank at right angles thereto and extending substantially equal distances from said shank; and resilient mounting means interposed between each of the

ends of said rock bar and said body flexibly securing said stylus assembly to said body in a position disposing the length of said rock bar at right angles to the direction of desired movement of said stylus to thereby permit angular movement of said rock bar in response to lateral displacement of said stylus.

12. In an electromagnetic phonograph pick-up, the combination of: a body member, a stylus assembly comprising a tubular stylus shank formed of magnetic material, a pointed record-engaging stylus secured in one end of said shank, and a rock bar of channel shaped cross section disposed with the plane of the web thereof at right angles to said shank and extending substantially equal distances from said shank; and resilient mounting means interposed between each of the ends of said rock bar and said body flexibly securing said stylus assembly to said body in a position disposing the length of said rock bar at right angles to the direction of desired movement of said stylus to thereby permit angular movement of said rock bar in response to lateral displacement of said stylus.

13. In an electromagnetic phonograph pick-up, the combination of: a body member; a stylus assembly comprising a rock bar of channel shaped cross section, and a tubular stylus shank secured to said rock bar intermediate ends thereof at right angles to the length of said shank having a generally tapered form disposed with the larger end at said rock bar, said shank having a substantially constant wall thickness along its length; and resilient mounting means interposed between each of the ends of said rock bar and said body for flexibly securing said stylus assembly to said body.

14. In an electromagnetic phonograph pick-up including a body member carrying means defining a pair of spaced magnetic pole faces, the combination of: a stylus assembly including an armature portion and a rock bar portion extending transversely of said armature portion; resilient blocks of polygonal cross section bonded to the ends of said rock bar portion; and means on said body member for engaging said blocks and normally holding said assembly in a position disposing said armature portion centrally between said pole faces and disposing said rock bar in a position disposing the length thereof at right angles to the direction of desired movement of said armature portion.
